UNITED STATES PATENT OFFICE.

EPHRAIM S. JOHNSON, OF JERSEY CITY, NEW JERSEY.

DESIGN FOR A PENCIL.

Specification forming part of Design No. 6,523, dated March 25, 1873.

To all whom it may concern:

Be it known that I, EPHRAIM S. JOHNSON, of Jersey City, in the county of Hudson and State of New Jersey, have invented a Design for Pen and Pencil Cases, of which the following is a specification:

The nature of my invention is fully represented in the accompanying drawing, in which letters of like name and kind indicate like parts in both the specification and drawing.

In the figure, *a a a a* represent bands of hard rubber, secured in any well-known manner upon and circumferentially around the inner cylinder or body of the case. *e e e* represent bands of gold secured to the inner cylinder or body of the pencil in the same manner as the bands of rubber are made and secured. *c* represents the balance or remainder of the pencil-case covered with slabs of mother-of-pearl or other desirable material. These bands of rubber and gold are placed alternately upon the cylinder so as to make a pleas-

ing contrast. These bands may extend over any portion of the length of the cylinder, and may be composed of any suitable material for the purpose of producing a contrast other than gold and hard rubber without affecting the objects of my design.

The distinctive features of my design are the alternating contrasting bands or rings, composed of different materials and colors upon the cylinder of the pen or pencil case, so as to produce a pleasing contrast.

These bands may be engraved and finished in any desired manner after being secured to the cylinder.

What I claim as my invention is—

The design for pen and pencil cases, herein shown, it being produced by alternate bands of contrasting colors, substantially as described.

EPHRAIM S. JOHNSON.
